CLAIM

I claim the ornamental design for a folding worship stand, as shown and described.

DESCRIPTION

FIG. 1 is a perspective view of a folding worship stand, illustrated in a deployed position with a pen compartment in a closed position, showing my new design;

FIG. 2 is a front elevational view thereof, illustrated in the deployed position with the pen compartment in the closed position;

FIG. 3 is a rear elevational view thereof, illustrated in the deployed position with the pen compartment in the closed position;

FIG. 4 is a left-side elevational view thereof, illustrated in the deployed position with the pen compartment in the closed position, the right-side elevational view being a mirror image thereof;

FIG. 5 is a top plan view thereof, illustrated in the deployed position;

FIG. 6 is a bottom plan view thereof, illustrated in the deployed position;

FIG. 7 is a perspective view thereof, illustrated in the deployed position with the pen compartment in an open position;

FIG. 8 is a perspective view thereof, illustrated in the deployed position with an arm rest in a lowered position;

FIG. 9 is a left-side elevational view thereof, illustrated in a collapsed position; and,

FIG. 10 is a perspective view thereof, illustrated in the collapsed position.
